[57] ABSTRACT

Certain fluorocarbon surfactants combined with certain silicone surfactants provide mixtures that reduce the surface tension of water to 19 dynes or less per centimeter, and when foamed are particularly effective in fighting fires involving lighter-than-water hydrophobic liquids. Mixtures are further improved with certain other surfactants and use less of the fluorocarbon surfactants to provide fire fighting effectiveness of prior art compositions which do not contain silicone surfactants. Hydrophilic resins and sequestering agents can also be contained in the mixtures.

16 Claims, No Drawings

FIRE FIGHTING

The present application is in part a continuation of application Ser. No. 131,763 filed April 6, 1971 and subsequently abandoned.

This invention relates to the fighting of fires with aqueous foam.

When gasoline or similar low density hydrophobic liquids are set afire, special fire-fighting materials are needed. Such fire-fighting materials should be spread very rapidly over the entire surface of the liquid inasmuch as the burning will continue at any location where the burning liquid is not covered. Fire-fighting foams stabilized by fluorocarbon surfactants as described in Tuve U.S. Pat. No. 3,258,423 granted June 28, 1966, or containing fluorocarbon surfactants as in French U.S. Pat. No. 3,562,156 granted Feb. 9, 1971, are very effective in rapidly spreading over a spill fire.

Among the objectives of the present invention is the provision of improved compositions for fighting such fires.

The foregoing as well as other objectives of the pre-

applied only on a portion of the layer. Likewise the silicone surfactant alone when applied similarly will not cause film-over. Filming-over or absence of filming-over can be observed by the extinguishment of flames from the burning heptane, or in the absence of burning by illuminating the heptane layer from above and viewing it by the light reflected from the surface. Viewed in this way the aqueous film is clearly distinguishable.

The spreading (filming-over) ability of any given water solution is different for different hydrocarbons. It has been noted for example that hydrocarbons having higher surface tensions and/or a lower content of methyl end-groups are easier to spread over with water films. For example Kerosene, or gasolines having a high content of aromatics, or cyclohexane, are covered with films very readily; but liquids like aviation gasoline, or isoctane (2,2,3-trimethylpentane) or even n-hexane are particularly difficult to film over.

As another illustration of the present invention a mixture of 80 parts of $(CF_3)_2CF(CF_2)_nCH_2SO_3^- M^+$ where n ranges from 4 to 8 and M is sodium, and 120 parts of

sent invention will be more fully understood from the following description of several of its exemplifications where all proportions are given by weight unless otherwise specified.

When certain fluorocarbon surfactants are mixed with certain silicone surfactants, the mixtures impart to water an unusually striking ability to spread as a film over burning gasoline and the like and thus extinguish all flames. Such mixtures also sharply reduce the surface tension of water as well as the interfacial tension between water and gasoline. The increase in spreadability is generally more effective than produced by either surfactant alone.

For example a mixture of equal parts of

and

where n ranges from 5 to 9, when dissolved in water in a combined concentration of 0.1% by weight reduces the surface tension of water at 25°C to the extremely low value of 17.5 dynes per centimeter, a value lower than any obtained when either surfactant is used alone at any concentration. Also the mixture when dissolved in water and blown with air to produce a foam, will quickly film over a layer of n-heptane, although the foam is applied to cover only 10% of the layer. The same fluorocarbon surfactant alone dissolved in water at 0.1% concentration and blown with air produces a foam that will not film over an n-heptane layer when

from 2 through 5 and averages 3, when dissolved in water in a combined concentration of 0.1% by weight, then foamed and applied over a layer of automotive gasoline will film over rapidly. However neither of the two components alone at the same weight concentration will cause filming-over of the gasoline, nor for that matter will they separately do so at any concentration.

Preferred fluorocarbon surfactants in accordance with this invention are the salts and amides of perfluorocarboxylic and perfluorosulfonic acids, and amphoteric water-solubilized compounds. These surfactants contain in their structure a hydrophobic and oleophobic perfluorinated or nearly perfluorinated chain of 6 to 15 carbons that is repellent to water and to hydrocarbons. Another part of their structure provides hydrophilic properties and can be of the anionic, cationic, or amphoteric type. Nonionic fluorocarbon surfactants are not as effective regardless of their structure, and are accordingly not preferred. Surfactants containing ester linkages are not desired inasmuch as such linkages hydrolyze on standing in water solution.

The following are typical fluorocarbon surfactants useful for the purposes of the present invention;

-continued

7 (29%) and 9 (balance)

M in the formulae stands for an alkali metal or the ammonium radical. Other suitable fluorocarbon surfactants are the anionic, cationic and amphoteric ones described in U.S. Pat. No. 3,475,333 granted Oct. 28, 1969 and in British Patent Specification Nos. 1,130,822 published Oct. 16, 1968, and 1,148,486 published Apr. 10, 1969.

Fluorocarbon surfactants in which the fluorocarbon chain is directly linked to a ring such as a benzene ring are not very effective for the purposes of the present

invention. The acyclic linking of such a chain to a ring, as by means of a sulfone, methylene or carbonyl group does provide a surfactant that gives good results. The present techniques for producing perfluorocarbon chains tend to simultaneously make chains of varying lengths so that it is less expensive to use a mixture of such chains. The sixth surfactant in the immediately preceding list, for instance, when mixed with analogous compounds in which the $(\text{CF}_2)_4$ is replaced by $(\text{CF}_2)_3$, $(\text{CF}_2)_5$, $(\text{CF}_2)_7$, and $(\text{CF}_2)_9$ respectively, is a much less expensive material to prepare. An analogous mixture having 6% CF_2 , about 19% $(\text{CF}_2)_3$, about 32% $(\text{CF}_2)_5$, about 28% $(\text{CF}_2)_7$ and the balance $(\text{CF}_2)_9$, makes a very effective fluorocarbon surfactant for the purposes of the present invention.

Typical silicone surfactants effective for the purposes of the present invention are anionic, amphoteric, or nonionic, have at least one hydrophilic portion, linked to a silicone, i.e. $\text{Si}-\text{O}-\text{Si}-$, structure that is otherwise fully methylated. Such a structure is hydrophobic and oleophilic so that it is repellent to water but attracted to hydrocarbon. Those hydrophilic portions most strongly hydrophilic such as sulfonates, carboxylates, aminosulfonates, and amine oxides, are preferred.

25 The following compounds are additional illustrative silicone surfactants suitable for the purposes of this invention:

Silicone surfactants tend to hydrolyze when kept for appreciable periods in water solutions that are even slightly acid so that cationic silicone surfactants, which are only effective in acid solutions, are not desired.

Preferred silicone surfactants have a silicone moiety containing two to seven silicones, and one hydrophilic moiety for every one-half to four silicones in the silicone moiety. Where two or more hydrophilic moieties are attached to the same silicon and there is one hydrophilic moiety for every one to one-and-a-half silicones in the silicone moiety, the silicone surfactants are so highly effective that the fluorocarbon surfactant content of the mixture of these two surfactants can be reduced to 7% and still provide highly desirable film formations. The last three silicone surfactants listed above are examples of these highly effective materials.

In general silicone surfactants can all be prepared by hydrolyzing a chlorosilane or mixture of chlorosilanes and condensing the siloxane thus produced with a hydrophilic reactant. For example the second siloxane surfactant listed above is prepared by reacting one mol of

(a product from cohydrolysis of trimethylchlorosilane and methylchlorosilane) with two mols of allylglycidylether over a platinum catalyst; then reacting the resulting product with two mols of N-methyltaurine in a mixture of water and isopropyl alcohol at reflux temperature.

The fifth silicone surfactant of the foregoing list of 13 is prepared by reacting tris-(trimethylsiloxy) silane over a platinum catalyst with allylglycidylether followed by reacting the resultant compound with N-methyltaurine. Tris-(trimethylsiloxy) silane can be prepared by the slow addition of trimethylsilanol to trichlorosilane in pyridine.

The sixth and seventh listed silicone surfactants and their preparation are described in U.S. Pat. Nos. 3,531,417 and 3,531,507 respectively.

The surfactants of the present invention can also be used in mixtures containing two or more fluorocarbon surfactants and/or two or more silicone surfactants, such as when the fluorocarbon surfactant is a mixture

-continued

having varying lengths of fluorocarbon chain as explained above. In general about 20 to 80% silicone surfactant and 20 to 80% fluorinated surfactant should be present in the mixtures.

25 It has also been discovered that the well known acetylenic glycol surfactants added as a third component provide a synergistic increase in filming-over effectiveness as well as a further decrease in surface tension. The acetylenic glycol surfactants can also have their glycol groups condensed with ethyleneoxide.

For example, a mixture of 1 part

35 2 parts of the first siloxane surfactant listed above, and 3 parts of the last-listed fluorocarbon surfactant, dissolved in water in a combined concentration of 0.1% by weight makes a very effective film-forming and fire extinguishing mixture. It reduces the surface tension of the water at 25°C to 16.6 dynes per centimeter, a value lower than can be obtained by the two latter surfactants in any proportion. In general only about 5% to 50% of the acetylenic glycol surfactant is incorporated in the total mixture of surfactants.

40 As described on pages 413-14 in the text entitled "NonIonic Surfactants" edited by Martin J. Schick and published 1967 by Marcel Dekker, Inc., New York City, the class of acetylenic glycol surfactants includes 45 the above-mentioned ethyleneoxide and polyethylene oxide ether derivatives, and all of them are suitable for synergistic use in accordance with the present invention.

55 For fire fighting it is desirable to use fluorocarbon surfactants at relatively low concentration, i.e. about 0.05 to 0.15%, preferably 0.1%, in the aqueous solution being foamed. Greater concentrations require excessive surfactant consumption to produce the large quantities of foam needed. However even the aqueous solution itself is awkward to store, so that the standard practice is to only store a concentrate and dilute it with water when the foam is to be made and used. Such concentrates can have 16 to 35 times the surfactant concentration of the diluted solution so that for such use the surfactants of the present invention should have an appropriately high solubility. In general perfluorocarbon chains having a length of over 16 carbons, and siloxanes having more than four silicones per hydro-

philic group, too severely restrict the water solubilities of surfactants containing them.

It is important to have the fire-fighting solution applied over the burning liquid in the form of a foam. The foam helps to smother the fire and also provides a reserve of water solution containing the aqueous film-forming ingredients that can spread over the burning surface. The application of unfoamed water solution will merely cause excess solution to drop through to the bottom of the burning liquid because of the density difference, and in this way become incapable of replenishing the aqueous film which is continuously being consumed by evaporation.

At the high dilution at which the filming over feature can still be used for fire-fighting, the fluorocarbon surfactant and silicone surfactant mixtures do not provide good foaming properties, and other standard surfactants which are good foamers and/or foam stabilizers can be incorporated to increase the foaming characteristics. Sodium laurylsulfate and the like are very good for this purpose although they do not contribute to filming-over.

The following are other examples of surfactants that upgrade the foam, and any of these or of the foregoing foamers can be used by themselves or in combinations, in a total concentration of about 5 to 200% and even up to 400% of the mixtures of fluorinated and silicone surfactants:

Individual or mixed sodium alcohol sulfates, where the alcohol is a normal primary alcohol having 8 to 20 carbon atoms per molecule
 Myristyldimethylamine oxide
 Lauryldimethylamine oxide
 Sodium laurylethersulfate
 Ammonium laurylether sulfate
 Sodium tridecylethersulfate
 Protein hydrolyzate

Surfactants that provide very good foam stability in sea water are also desirable, particularly for concentrates of the present invention that otherwise show poorer foam stability when diluted with sea water, and yet may be needed for use on shipboard for example, where sea water is the only available diluent. Oleyl alcohol ethoxylate having 20 to 25 ethoxy groups per molecule is a particularly suitable sea water foam stabilizer, as are other heavily ethoxylated surfactants.

Foam-enhancing can also be effected by the addition of a solvent which has the added advantages of helping to release the aqueous film-forming agents from the foam and of providing antifreeze action in cold climate. The following solvents have been found to be very useful in this way:

2,5-pentanediol	ethylene glycol
t-butyl alcohol	1-butoxyethoxy-propanol-2
isopropyl alcohol	tetraethylene glycol
butyl carbitol	1,2,6-hexanetriol
dibutyl carbitol	isobutyl cellosolve

The fire-fighting effectiveness of a water solution of the present invention is further improved by dissolving in it a synthetic or natural hydrophilic resin. About $\frac{1}{8}$ to $\frac{1}{3}$ of such additive based on the combined weight of the fluorocarbon and silicone surfactants, causes the solution to extinguish flames more rapidly, and also more effectively keeps the extinguished liquid from re-igniting. While any natural or synthetic gum such as carragheen or locust bean gum can be used, water-

solubilized copolymerization products of maleic anhydride and ethylene or of maleic anhydride and methylvinylether are preferred, particularly where the copolymer is reacted with 3-dimethylaminopropylamine to form a half acid-half amino amide, and thus produce a polyampholyte type structure. Such a material is prepared by taking the ethylenemaleic anhydride polymer described in U.S. Pat. No. 2,396,785 granted Mar. 19, 1946 and gradually adding it in small portions to an equivalent amount of 3-dimethylamino propylamine dissolved in four times its weight of water. The equivalency is based on the reaction of 1 mol of the amine with each anhydride group. Water is also added gradually to keep the reaction mixture stirrable. The mixture is stirred at room temperature for eleven hours after the addition is completed, neutralized with dilute HCl and filtered. The resulting aqueous solution is ready for use. It increases water retention in foams by large amounts as indicated by typical data below:

Time, Min.	% WATER RETAINED		
	5	10	15
typical foam with 0.2% polymer	57	40	32
same foam without polymer	36	21	15

The resinous copolymers of the types indicated above and shown in U.S. Pat. No. 3,531,427, 2,378,629 and 3,388,106 granted Sept. 29, 1970, June 19, 1945 June 11, 1968 respectively can also be used in place of the ethylene-maleic anhydride copolymer referred to above. Preferred copolymers of these types have a monomer ratio of from 40:60 to 60:40.

Polyvinyl pyrrolidones and polyacrylic acids having molecular weights of 500 or more, and the water-soluble salts of the polyacrylic acids, can also be used as hydrophilic gum in accordance with the present invention. Preferred molecular weights of any hydrophilic resin used are above 100,000.

The addition of hydrophilic resins to the fire-fighting concentrates of the present invention also increases the viscosity of the concentrates. This is helpful in assuring more precise proportioning of the concentrates with water, as for instance when using gear-type proportioning pumps such as the Hale Proportioning Water Pump. Thus a concentrate viscosity of about 4 to 6 centistokes may be desired with such pumps. Where the concentrates undergo vigorous agitation during proportioning it is also helpful to have viscosity-increasing additives that do not show the usual thixotropic viscosity drop during such agitation. A portion of the viscosity increase can thus be effected with a dilatant type of additive such as partially hydrolyzed protein or a soluble grade gelatin.

The foam-forming concentrates of the present invention are most stable in alkaline condition, and it is accordingly preferred that they be slightly alkaline, that is have a pH at least as high as 7.8. A pH higher than 8 does not further increase the stability and is not desired. The concentrates can also contain buffers that maintain alkalinity even when the concentrates are mixed with other foam-forming concentrates that may be acid. Any compatible buffer or buffer mixture can be used, even sodium bicarbonate, but it is preferred to use tris-hydroxymethyl aminomethane. The amount of buffering should be enough to take care of about 100% addition of an acid foam-forming concentrate which

can be considered as having an acid content equivalent of 2 grams of H_2SO_4 per liter.

The concentration of fluorocarbon surfactant that produces effective filming can be reduced somewhat when the firefighting solution of the present invention contains a small amount, e.g. about 0.003 to 0.01% of a sequestering agent such as alkali metal salts of nitrilo-triaceitic acid or of ethylene diamine tetraacetic acid.

The following examples of preferred foam-forming concentrates and tests show the results achieved pursuant to the present invention. In Examples I, II and III fire tests were conducted in a circular pan having a surface area of 33 square feet into which two inches of fuel was placed, the fuel lit and permitted to burn as specified (pre-burn time), after which the foam mixtures were applied at the rate of 0.06 gallons of concentrate per minute per square foot, diluted with additional water as indicated, until the fire was completely extinguished. All times after the pre-burn were measured from the beginning of the foam application.

foams made from aqueous mixtures of a fluorocarbon
and silicone surfactant, but the fluorocarbon surfactant
of such mixtures is indicated as being insoluble in water
and ineffective by itself, although when in a concentra-
tion of 0.2% and dispersed with the help of the silicone
surfactant, it does produce a fire-fighting foam. This
concentration is greater than the maximum fluorocar-
bon surfactant content in the fire-fighting foams of the
present invention, and much greater than the fluoro-
carbon surfactant content of the foams produced from
the working examples of the present application. More-
over this Belgian patent discloses the use of a silicone
surfactant in a concentration of 2%, ten times that of its
excessive fluorocarbon surfactant concentration, thus
further emphasizing the disparity with respect to the
present invention.

With the help of a small amount of an amino polycar-
boxy sequestering agent the concentration of fluoro-
carbon surfactant in the diluted concentrate as applied
to the fire, may be decreased to less than 0.06%. The
sequestering agent content need only be between about
one-twelfth to about one-fourth that of the fluorocar-
bon surfactant for this desirable result.

The heavily ethoxylated foamer oleyl alcohol ethoxy-
lates containing 20 to 25 ethoxy groups per molecule,
can be used in a concentration of 19.6 grams per gal. of
concentrate that is to be diluted to 16-2/3 times its
volume. This foamer can be replaced by other such
surfactants having at least about 20 consecutive ethyl-
ene oxide units per mol in a single terminal chain and a
hydrophobic chain of at least 14 carbons, and in an
amount about one-sixth to about equal that of the fluo-
rocarbon surfactant, to give the desired fire-fighting
effectiveness after dilution with sea water, using less
than 0.09% fluorocarbon surfactant in the diluted ma-
terial.

In all the working examples given above, the surface
tension of the fire-fighting solutions formed is less than
18 dynes/cm., and the solutions rapidly film over burn-
ing aviation gasoline.

Obviously many modifications and variations of the
present invention are possible in the light of the above
teachings. It is, therefore, to be understood that within
the scope of the appended claims the invention may be
practiced otherwise than as specifically described.

What is claimed:

1. An aqueous film-forming foamable liquid having a
surface tension at least as low as 19 dynes per centime-
ter and having dissolved in it a mixture of a water-solu-
ble fluorocarbon surfactant and a water-soluble sili-
cone surfactant, the fluorocarbon surfactant having a
hydrophobic perfluorinated carbon chain acyclically
connected to a hydrophilic moiety and being anionic,
amphoteric or cationic, the silicone surfactant being
anionic, nonionic or amphoteric, having a silicone moi-

Omission of the polymer as in Examples IV and V
reduces the resistance to re-ignition and slightly delays
the fire extinguishing times. Omission of the glycols, as
in Examples IV, V and VI has no significant effect on
the fire extinguishing times or the resistance to re-ignition.

Of special significance are film-forming formulations
in which all the surfactants are amphoteric or of am-
photeric nature. Thus while the silicone of Example I
does not have the classical zwitterion structure, its
nitrogens do tend to become protonated and it shows
no adverse reaction to quaternary surfactants. It ac-
cordingly has an amphoteric nature and when com-
bined with an amphoteric fluorinated surfactant and
amphoteric supplemental foamers such as decyldime-
thylamine oxide or octyl-dimethylamino propane sul-
fonic acid betaine, provides a foam-forming concen-
trate that is compatible with all other foam-forming
concentrates. The hydrophilic resin of Example I is also
amphoteric and can be added to such an amphoteric
type of combination to further improve its fire-fighting
effectiveness without detracting from its compatibility.

The following formulation is also a very good univer-
sal type concentrate that can be mixed with any other
commercial concentrate.

EXAMPLE VII

$\text{C}_7\text{F}_{15}\text{CONH}(\text{CH}_2)_3\text{N}^+(\text{CH}_3)_2\text{CH}_2\text{CH}_2\text{COO}^-$	52 g.

Decyldimethylamine oxide	178 g.
Octyldimethylamine oxide	76 g.
Octyldimethylamino propane sulfonic acid betaine	166 g.
Dodecyldimethylamino propane sulfonic acid betaine	60 g.
Ethylene glycol	188 g.
Polymer of Example I	20 g.
Water	to 1 gallon

A feature of the present invention is that it enables
the production of commercial fire-fighting foam con-
centrates of the filming-over type in which the concen-
tration of fluorocarbon surfactant is appreciably lower
than in those commercial concentrates that do not

ety containing two to seven silicones, a hydrophilic moiety for every one-half to four silicones in the silicone moiety, its silicone moiety being otherwise fully methylated, the mixture having about 20 to 80% of the fluorocarbon surfactant and 80 to 20% of the silicone surfactant and the fluorocarbon surfactant being in a concentration of from about 0.05 to about 0.15 percent in the aqueous liquid being foamed.

2. An aqueous foam-forming concentrate having a dissolved mixture of a water-soluble fluorocarbon surfactant and water-soluble silicone surfactant, the fluorocarbon surfactant having a hydrophobic perfluorinated carbon chain acyclically connected to a hydrophilic moiety and being anionic, amphoteric or cationic, the silicone surfactant being anionic, nonionic or amphoteric, having a silicone moiety containing two to seven silicones, a hydrophilic moiety for every one-half to four silicones, a hydrophilic moiety for every one-half to four silicones in the silicone moiety, its silicone moiety being otherwise fully methylated, and the mixture having about 20 to 80% of the fluorocarbon surfactant and 80 to 20% of the.

3. The concentrate of claim 2 which is slightly alkaline.

4. The concentrate of claim 3 in which there is also dissolved a hydrophilic resin in an amount about one-eighth to about one-third of the surfactant mixture.

5. The concentrate of claim 4 in which there is also dissolved a foam-building surfactant in an amount about 5 to 400% of the mixture of fluorocarbon and silicone surfactants.

6. The concentrate of claim 4 which also contains a buffer that keeps it from becoming acid when mixed with about an equal amount of an acid foam-forming concentrate.

7. The concentrate of claim 2 in which there is also dissolved a hydrophilic resin in an amount about one-eighth to about one-third of the surfactant mixture.

8. The combination of claim 2 in which there is also dissolved a foam-building surfactant in an amount about 5 to 400% of the mixture of fluorocarbon and silicone surfactants.

9. The concentrate of claim 3 which has a designated degree of dilution, at which dilution the mixture of silicone and fluorocarbon surfactants do not provide fire-fighting foamability, there being also dissolved in the concentrate in an amount about 5 to 400% of the

mixture of fluorocarbon and silicone surfactants, at least one foam builder that is neither a silicone nor a fluorocarbon surfactant to bring its foamability at said dilution to fire-fighting level.

5 10. The concentrates of claim 9 which also contains a buffer that keeps it from becoming acid when mixed with about an equal amount of an acid foam-forming concentrate.

11. The liquid of claim 1 in which there is also dissolved in the film-forming liquid an acetylenic glycol surfactant in an amount from about 5 to 50% of the mixture of fluorocarbon and silicone surfactants.

12. The liquid of claim 1 in which the surface tension is at least as low as 18 dynes per centimeter.

15 13. An aqueous foamable film-forming liquid having a surface tension at least as low as 19 dynes per centimeter and having dissolved in it a mixture of a water-soluble fluorocarbon surfactant and a water-soluble silicone surfactant, the fluorocarbon surfactant having a hydrophobic perfluorinated carbon chain acyclically connected to a hydrophilic moiety and being anionic, amphoteric or cationic, the silicone surfactant being anionic, nonionic or amphoteric, having a silicone moiety containing two to seven silicones, a hydrophilic moiety for every one to one-and-a-half silicones in the silicone moiety and at least two hydrophilic moieties attached to the same silicon, the silicone moiety being otherwise fully methylated, the mixture having about 7 to 80% of the fluorocarbon surfactant and 93 to 20% of the silicone surfactant and the fluorocarbon surfactant being in a concentration of from about 0.05 to about 0.15 percent of the aqueous foamable liquid.

20 25 30 35 40 45 14. The concentrate of claim 10 in which the buffer is tris(hydroxymethyl)amino methane.

15. The concentrate of claim 2 which has a designated degree of dilution and the concentration of the fluorocarbon surfactant in the concentrate is such that upon the designated dilution that concentration becomes between about 0.05 and about 0.15 percent of the aqueous foamable liquid.

16. The liquid of claim 1 in which the silicone and fluorocarbon surfactant mixture does not provide fire-fighting foamability to the liquid, the foamability being brought up to fire-fighting level by at least one foam-building surfactant that is neither a silicone nor a fluorocarbon surfactant.

UNITED STATES PATENT AND TRADEMARK OFFICE
CERTIFICATE OF CORRECTION

PATENT NO. : 3,957,658

Page 1 of 2

DATED : May 18, 1976

INVENTOR(S) : Peter J. Chiesa, Jr. and Louis R. DiMaio

It is certified that error appears in the above-identified patent and that said Letters Patent are hereby corrected as shown below:

Col. 2, the line after line 22 should read:

Col. 5. in the fourth structural formula

Col. 5, line numbered 55, "foregiong" should be --foregoing--.

Col 7 line 23. "following" should be --following--.

2-1 2 the table following line 19 should read:

% WATER RETAINED

Time, Min.	5	10	15
typical foam			
with 0.2% polymer	57	40	32
same foam			
without polymer	36	21	15

UNITED STATES PATENT AND TRADEMARK OFFICE
CERTIFICATE OF CORRECTION

PATENT NO. : 3,957,658
DATED : May 18, 1976
INVENTOR(S) : Peter J. Chiesa, Jr. and Louis R. DiMaio

Page 2 of 2

It is certified that error appears in the above-identified patent and that said Letters Patent are hereby corrected as shown below:

Col. 8, line numbered 30, --and-- should be inserted after "1945".

Col. 8, line numbered 58, "accordngly" should be --accordingly--.

Col. 9, line 15, "foam" should be --foamed--.

Col. 9, twelfth line under "Example I", "retention date" should be --retention data--.

Col. 9, fourth line under "Example III", "(CH₃)C C--" should be -- (CH₃)C≡C-- --.

Col. 13, last line of claim 2 should read --and 80 to 20% of the silicone surfactant.--

Col. 13, in the first line of claim 8, "combination" should be --concentrate--.

Col. 14, in the first line of claim 10, "concentrates" should be --concentrate--.
